(57) **CLAIM**

The ornamental design of an in-bath filler and overflow unit, as shown and described.

DESCRIPTION

FIG. 1 is a top, front, right side perspective view of an in-bath filler and overflow unit of my new design;

FIG. 2 is a front elevational view of the in-bath filler and overflow unit of FIG. 1;

FIG. 3 is a rear elevational view of the in-bath filler and overflow unit of FIG. 1;

FIG. 4 is a side elevational view of the in-bath filler and overflow unit of FIG. 1, with the other side being the mirror image of the view in FIG. 4;

FIG. 5 is a top plan view of the in-bath filler and overflow unit of FIG. 1; and,

FIG. 6 is a bottom plan view of the in-bath filler and overflow unit of FIG. 1.

The dashed broken lines depict portions of the in-bath filler and overflow unit that form no part of the claim.
